US00D964465S

(12) United States Design Patent (10) Patent No.: US D964,465 S
Samson et al. (45) Date of Patent: * Sep. 20, 2022

(54) GAME LAYOUT

(71) Applicant: Sandstone Media, LLC, Las Vegas, NV (US)

(72) Inventors: James Samson, Los Angeles, CA (US); Kyle Rosenblum, Los Angeles, CA (US); Jonathan Sanford, Los Angeles, CA (US); Mark Manuel, Los Angeles, CA (US)

(73) Assignee: Sandstone Media, LLC, Las Vegas, NV (US)

() Term: 15 Years

(21) Appl. No.: 29/764,674

(22) Filed: Dec. 31, 2020

(51) LOC (13) Cl. 21-01

(52) U.S. Cl.

USPC D21/338

(58) Field of Classification Search

CLAIM

The ornamental design for a game layout, as shown and described.

DESCRIPTION

FIG. 1 is a front perspective view of a game layout showing our new design;

FIG. 2 is a front elevational view thereof;

FIG. 3 is a rear elevational view thereof;

FIG. 4 is a top plan view thereof;

FIG. 5 is a right side elevational view thereof; and,

FIG. 6 is a left side elevational view thereof.

The broken line portions of the game layout form no part of the claimed design.

1 Claim, 5 Drawing Sheets
